UNITED STATES PATENT OFFICE.

ARTHUR Q. WALSH, OF NEW YORK, N. Y.

DESIGN FOR A PIPE.

SPECIFICATION forming part of Design No. 34,749, dated July 9, 1901.

Application filed May 1, 1901. Serial No. 58,400. Term of patent 3½ years.

To all whom it may concern:

Be it known that I, ARTHUR Q. WALSH, a subject of the King of England, and a resident of the city of New York, borough of Manhattan, in the county and State of New York, have invented and produced a new and original Design for a Pipe, of which the following is a specification, reference being had to the accompanying drawing, forming a part thereof, in which is represented a perspective view of a pipe embodying the features of my design.

The design consists of the pipe, as shown, the body A of which is of pan-like form, with the handle B departing therefrom at an angle and with a ring-like extension C at the upper end of the body A, the said ring and band

presenting circular panels, the upwardly-flaring exterior lines of the ring being continuous of the similarly-flaring lines of the body A.

Having thus described my invention, I claim as new and desire to secure by Letters Patent—

The design for a pipe herein shown and described.

In testimony whereof I have signed my name to this specification in the presence of two subscribing witnesses.

ARTHUR Q. WALSH.
